UNITED STATES PATENT OFFICE.

ARTHUR LIPSCHUTZ, OF ST. LOUIS, MISSOURI.

TRUCK AND BODY BOLSTER.

SPECIFICATION forming part of Letters Patent No. 738,214, dated September 8, 1903.

Application filed January 24, 1903. Serial No. 140,362. (No model.)

To all whom it may concern:

Be it known that I, ARTHUR LIPSCHUTZ, a resident of the city of St. Louis, State of Missouri, have invented certain new and useful improvements in Truck and Body Bolsters, of which the following is a specification.

My invention relates to truck and body bolsters for railroad-cars, and the object of my invention is to provide a strong all-metal bolster of less weight and cost than the bolsters which are now in use.

A particular object of my invention is to provide a truck or body bolster or like element in which ordinary rolled or structural steel shapes—such as channel-bars, I-beams, and the like—may be employed without alteration in shape.

My invention consists primarily in a new article of manufacture comprising a pressed-steel truss having a solid web that is rimmed by a flange that follows the complete outline of the truss.

Further, my invention consists in a bolster or other car element, comprising a rolled-steel beam and a truss of the foregoing description, having its long flange riveted to the flange of said beam; and, further, my invention consists in various details of construction and in combinations of parts, all as hereinafter described, and particularly pointed out in the claims.

The invention will be more readily understood by reference to the accompanying drawings, forming a part of this specification, and in which—

Figure 1 illustrates a car element embodying my invention. Fig. 2 is an elevation of a complete bolster. Fig. 3 is an enlarged section on the line *x x* of Fig. 2. Fig. 4 is a section on the line *y y* of Fig. 2, and Fig. 5 is a section showing the element containing an I-beam.

The most practical form of my invention includes a rolled channel 2 or a rolled I-beam 3, these being commercial shapes which can be readily obtained in various sizes as required in the manufacture of bolsters or other car elements for cars of different carrying capacities. Other and different beams and shapes may be utilized within the scope of my invention, though not economically adapted to bolster construction. The gist of this in-

vention resides in a pressed-steel individual truss having a continuous flange or rim which is riveted to the flange of the longer beam. 55

The simple bolster or element of my invention comprises a rolled channel 2, or a rolled I-beam 3, and a shorter truss 4, that is riveted to the lower flange of the beam, with its web 4' in alinement with the web of the beam—60 that is, in the same vertical plane. The truss comprises said web 4' and the continuous flange or rim 4'', the longest straight portion or side of which is applied to the flange of the beam. As shown, the flange or rim of the 65 truss conforms to the outline of the truss, which, as shown, is of varying depth and is provided with a flat bottom 4''', that is a portion of the flange 4''. In the case of a car bolster the center plate is attached to said 70 flat portion 4'''. This simple element is suitable for employment as a body-bolster for a light car, and when equipped with column-guides, such as 5, is a very good truck-bolster for such a car, presenting a maximum of 75 strength in a minimum weight of material. The center bolt 7 may pass through the flanges of the beam only or through all the flanges, as shown. A still heavier bolster is made with I-beams 3 in place of the channel-beams. The truck-center 6 may be attached to the top of the truck-bolster or to the bottom of the truss, if in a body-bolster, in any 80 suitable manner.

It is obvious that numerous modifications 85 of my invention will readily suggest themselves to one skilled in the art, and I therefore do not confine the invention to the specific constructions herein shown and described. 90

Having thus described my invention, I claim as new and desire to secure by Letters Patent—

1. The car element, comprising the flanged steel beam, in combination, with the truss 95 provided with a continuous flange or rim, the longest portion of which is riveted to the flange of said beam, substantially as described.

2. The car element, comprising the rolled 100 beam of uniform cross-section, in combination, with the pressed-steel truss, comprising a web of varying depth and a continuous flange or rim, the long portion of which is

riveted to the flange of said beam, substantially as described.

3. The car - bolster comprising the rolled beam of uniform cross-section, having a vertical web, in combination, with the pressed-steel truss comprising a web of varying depth, alined with the web of the beam, and a continuous flange or rim, the long portion of which is riveted to the flange of said beam

and suitable column-guides upon said beam, substantially as described.

In testimony whereof I have hereunto set my hand this 17th day of January, 1903.

ARTHUR LIPSCHUTZ.
